UNITED STATES PATENT OFFICE.

WEBSTER C. ESTES, OF FLATBUSH, NEW YORK.

DESIGN FOR A BOX.

SPECIFICATION forming part of Design No. 20,519, dated February 10, 1891.

Application filed January 19, 1891. Serial No. 378,359. Term of patent 7 years.

To all whom it may concern:

Be it known that I, WEBSTER C. ESTES, a citizen of the United States, residing at Flatbush, in the county of Kings and State of New York, have invented a Design for a Wooden Box, of which the following is a specification.

This design for a wooden box is represented in the accompanying drawing by a vertical section.

The article is round, and the principal feature of the design is the ornamental shape and configuration of the exterior surface as represented.

The design of the round box-body is sectionally a compound curve at *a* with a cove at *b* and curved base *c*. The design of the rim of the cover is a compound curve at *d* and a rib at *e*. 15

I claim—

The design of the exterior shape and configuration of the round wooden box, substantially as described and represented. 20

Signed by me this 15th day of January, 1891.

WEBSTER C. ESTES.
